DOOR LATCH MECHANISM

Gotthard Hagstrom, Greenwich, Conn., assignor
to The Safe Padlock and Hardware Company,
Lancaster, Pa., a corporation of Pennsylvania

Application August 11, 1950, Serial No. 178,897

11 Claims. (Cl. 292—169)

1

My present invention relates to certain improvements in door latch mechanisms; and the nature and objects of the invention will be readily recognized by those skilled in the arts involved in the light of the following explanation and detailed description of the accompanying drawings illustrating what I at present consider to be the preferred embodiments or mechanical expressions of the invention from among various other forms, designs, arrangements, embodiments, modifications, variations, combinations and constructions, of which the invention is capable within the broad spirit and scope thereof as defined by the appended claims.

The invention is concerned generally with those types of door locking, latch mechanisms primarily intended for, although not limited to, use on inside doors, such as bathroom, bedroom and the like doors, where privacy rather than security is the essential purpose of the latch mechanism. Such types of latch mechanism provide for releasable locking thereof with the door shut, by a person at the inner side of the door against opening thereof from the outside by normal outside knob operation. When locked, this type of latch mechanism is thereafter released automatically by normal operation of the inner knob for retraction of the latch mechanism to open the door. Usually the latch mechanism is provided with a manual operating member thereon or associated therewith at the inner side of the door for effecting locking of the latch against outside knob operation thereof with the door closed. Such a member may take the form of a latch-lock operating button mounted in the inner door knob, and it is to this particular form of such types of latch mechanism to which my present invention is especially directed. The invention is not, however, limited as to all features, constructions or combinations thereof, to embodiment with door locking, latch mechanisms of the form having an inner knob-mounted latch lock operating member, as will be further developed hereinafter.

An object of the invention is to provide a door locking, latch mechanism of the general types hereinabove characterized, which is of a structurally and mechanically simple design capable of relatively low cost quantity production, yet which provides a lock mechanism of a positive operating, precision type which will retain its precision and efficiency of operation over a relatively long operating life under the various conditions to which such a latch mechanism may be subjected in normal operation and use.

2

Another object is to provide an improved design and construction of such a door locking, latch mechanism which may be readily, positively locked by a person at the inside of a door against opening of the door from the outside, but which will function to automatically release the latch mechanism from locked position upon closing of the door in the event that the latch mechanism has been locked with the door open.

Another object is to provide for emergency unlocking of such a latch mechanism from the outside with the door closed, without damage to the mechanism and by the use of any commonly available instrumentality to thereby eliminate the necessity for a special tool or implement for such an emergency operation.

A further object is to provide such a latch mechanism which when in its latch-locked or dogging position, will be released and unlocked automatically by either door opening operation of the inner knob or by depression or retraction of the latch bolt of the mechanism independently of knob operation.

A feature of the invention in carrying out the foregoing general object resides in the utilization of a single, unitary spindle mounting thereon and operated by inner and outer door knobs, with the inner door knob having limited rotation relative to the spindle for effecting releasing or undogging operation of the latch lock from its locked position.

Another object is to provide for automatic self-centering of such a lost motion mounted door knob on the latch operating spindle, in order that, following lock releasing rotation of the inner door knob relative to the spindle, such knob will be returned to its normal or centered position on the spindle.

Another general object is to provide a design and construction of door latch mechanism including an operating spindle and inner and outer door knobs mounted thereon, in which the necessity for the use of screws on the inside door knob and on the inside and outside roses for the knobs is eliminated.

A further object is to provide such a door latch mechanism which is capable of adjustment without the necessity of special tools or equipment and merely by the act of bending one of the elements of the mechanism, to enable the mechanism to be installed on and used with doors of different thicknesses.

A feature of the invention in carrying out the above object of latch mechanism adjustment for doors of different thicknesses is found in the pro-

vision of a simple yoke member operably coupling the latch bolt of the latch unit with the latch locking mechanism for actuating the latter to released, undogging position by retraction or depression of the latch bolt, with such yoke member having one leg thereof bendable to a position of angular adjustment to adjust the yoke to the width of a door on which the latch mechanism is to be installed.

A further object is to provide an efficient and improved construction of tubular latch bolt unit particularly useful as a component of the door locking, latch mechanism of my present invention but which is also capable of general use as a tubular latch bolt unit for other forms and types of door latch mechanisms.

With the foregoing and various other objects, features and results in view, which others will be readily apparent from the following detailed description and explanation, my invention consists in certain novel features in design and construction, and in combinations and sub-combinations of parts and elements, all as will be more fully referred to and specified hereinafter.

Referring to the accompanying drawings, in which similar reference characters refer to corresponding parts and elements throughout the several figures thereof:

Fig. 1 is a view in outer edge elevation of a portion of a door having installed therein a latch mechanism of my invention, the inner and outer knobs being shown in side elevation and the latch bolt being shown in end elevation.

Fig. 2 is a view in horizontal section through the door and latch mechanism of Fig. 1, taken as on the line 2-2 of Fig. 1, with the mechanism in unlocked position.

Fig. 3 is a view in vertical, longitudinal section through the tubular latch bolt unit of the mechanism of Figs. 1 and 2, taken as on the line 3-3 of Fig. 2.

Fig. 4 is a detailed view in transverse section through the inner knob push button shank or pin, taken as on the line 4-4 of Fig. 2.

Fig. 5 is a view in transverse section through the outer end of the inner knob insert and spindle, taken as on the line 5-5 of Fig. 2, and showing the provision for limited movement of the inner knob and its insert or hub relative to the spindle.

Fig. 6 is a view in transverse section through the inner knob insert or hub taken as on the line 6-6 of Fig. 2, and showing the spring loaded balls of the inner knob self centering means.

Fig. 7 is a view in vertical section through the door mounted latch mechanism of Fig. 1, taken as on the line 7-7 of Fig. 2.

Fig. 8 is a view in vertical section through the door mounted latch mechanism of Fig. 1, being a view similar to Fig. 2, but showing the mechanism in locked or dogged position.

Fig. 9 is a view in vertical transverse section taken as on the line 9-9 of Fig. 8, and showing particularly the latch plate and spring loaded latch slidably mounted thereon.

Fig. 10 is an exploded view illustrating in perspective the parts and components making up the latch mechanism of Fig. 1, with such parts and components being shown separated but in the relative positions thereof to be assumed in assembly.

Fig. 11 is a detail perspective view of the push rod for the locking sleeve.

Fig. 12 is a detail view in side elevation of the coined, sleeve receiving end of the push rod with

the side of the sleeve mounted therein shown in transverse section.

An embodiment of a latching mechanism of the invention of a type utilizing inner and outer door knobs mounted on a latch bolt actuating spindle intended for use on an inside door, has been selected by way of an example and not in all respects of limitation, for purposes of illustration and explanation. Such example latch mechanism is shown in Fig. 1 of the drawings in mounted and installed position on an inside door D of more or less conventional type. This example latch mechanism, referring now to Figs. 2 and 3 in connection with Fig. 1, includes the tubular latch bolt unit L, an actuating spindle S mounted in position extending transversely through and in operative association with the latch unit L, and inner and outer knobs I and O mounted on the opposite inner and outer ends, respectively, of spindle S for rotation of the spindle to actuate the latch bolt unit.

General assembly

The latch bolt unit L is mounted in horizontally disposed position in a mortised, bored, or otherwise formed, opening 2 which extends into the body of the door D through the free edge 3 thereof. The spindle S is mounted in position extended transversely through the door D and the latch unit L, through a circular bored opening 4 which extends transversely through the door across and intersects opening 2, with the axes of these bores 2 and 4 being perpendicular to each other. The forward, outer end of unit L is provided with a vertically disposed face plate 107 attached to a back plate 105 secured on the forward end of case 100. Unit L is mounted in position in opening 2, in the usual manner by attaching the plates 105 and 107 to the door edge by screws 107a, as shown by Figs. 1, 2 and 3.

The spindle S is, in accordance with my present invention as expressed in this example thereof, formed as a single, unitary member which is longitudinally fluted to provide the longitudinally disposed grooves 10 spaced equal distances apart therearound and being extended throughout the length and opening at their opposite ends through the ends of the spindle L (see Figs. 4 through 8). Spindle S thus formed, has in effect a square cross section. The spindle S is provided with external screw threading 11 on the end length thereof which projects beyond the outer side of door D in installed position, for threading thereonto of the outer door knob unit O. The spindle S is primarily supported in its horizontally disposed position at the central or intermediate portion thereof which extends through and is received in associated structure and elements of the latch bolt unit L.

At the outer side of the door, over and across the outer end opening of the spindle receiving bore 4, there is positioned a back plate 12 (see Figs. 7 and 10), which in this instance may be considered to be of rectangular plan form having a width less than the width of the bore 4 but a length greater than such bore for seating at its opposite ends against the outer surface of the door. The opposite end edges 12a of back plate 12 are formed of arcuate, outwardly curved shape transversely of the plate. The back plate 12 is provided with a central bore or opening 12b therethrough of a greater internal diameter than the external diameter or maximum width of spindle S, for receiving therethrough the spindle

S in assembled position of the latch mechanism. Bores 12c are provided extending through back plate 12 along the longitudinal center thereof spaced respectively above and below spindle receiving opening 12b.

An outside rose 14 is provided of circular form having an axial bore therethrough formed by an annular inturned flange portion 14a, and a peripheral annular inturned flange 14b for mounting on and over the arcuate edges 12a of back plate 12 to attach the rose to the plate. The internal diameter of flange 14b is substantially equal to the diameter of a circle of which the curved edges 12a of back plate 12 form arcs, so that, the rose 14 can be forced on and over back plate 12 with the inturned flange 14b of the rose tightly engaged over and across the curved edges 12a of back plate 12 with a pressed fit.

At the inner side of the door D extending over and across the inner end of spindle receiving bore 4, there is positioned a latch plate 20 of generally rectangular plan form having a central opening 21 therethrough of square shape defined by inwardly, laterally bent tabs or flanges 12a therearound. This square opening 21 is provided for receiving therethrough the spindle S in assembled position of the mechanism, the width of the square opening 21 being greater than the maximum external diameter or width of the spindle S. The latch plate 20 which is of generally rectangular shape, has a greater length than width and is positioned with its length horizontally disposed. The opposite end edges 20a of latch plate 20 are arcuate or curved transversely of the plate, as will be clear by reference to Fig. 10 in particular. Tapped bores 20b are formed through the latch plate 20 along its vertical or transverse center, spaced above and below the square opening 21 of the plate.

An inside rose 15 is provided of circular form having an axial bore therethrough defined by an inwardly turned annular flange 15a. Inner rose 15 is formed with an inturned peripheral flange 15b therearound having an internal diameter substantially equal to the diameter of the circle of which the curved opposite edges 20a of latch plate 20 form arcs, so that, rose 15 may be mounted and attached in assembled position on plate 20 with the flange 15b thereof engaged tightly over and across curved edges 20a with a pressed fit.

In assembled, installed position of the latch mechanism on a door, such as the door D of this example, the back plate 12 and the latch plate 20 are connected and drawn tightly together against the outer and inner sides of door D over the adjacent end openings, respectively, of bore 4 by the threaded and headed bolts or long screws 16 which are extended inwardly through bores 12c of back plate 12 with their inner threaded ends 16a threaded into the tapped bores 20b of latch plate 20, and their outer headed ends 16b engaged against back plate 12. The outer rose 14 and the inner rose 15 are attached to the back plate 12 and latch plate 20 in the manner hereinbefore described, so that, no screws or other fastening members are required in or through either rose, yet the roses are securely fixed in position over and closing the bore 4 through the door to provide by their central inturned flange portions 14a and 15a, the knob hub seats or supplemental bearings for the outer and inner knobs O and I, respectively.

By the foregoing construction and arrangement, not only is the necessity for screws or

fastening members in the inner and outer roses B eliminated, but the assembly is rendered adjustable so as to be readily adapted for installation on doors of varying thicknesses. This is made possible by the inherent adjustability of the spacing possible between the back plate 12 and the latch plate 20 due to the use of the threaded long screws 16 by which these plates are connected together for spacing adjustment therebetween, so that the plates may be clamped in installed position against the inner and outer sides of doors of different thicknesses.

The outer knob O comprises a unit formed of a shank 17 secured on and over an insert member or hub 18 having an internally threaded bore 18a therethrough, and a knob forming cap member 19 secured at its inner side to the outer annular flange portion 17a of shank 17. A tapped bore 18b is formed radially through shank 17 and into hub 18 for receiving the usual set or lock screw 18c (see Fig. 10) for locking outer knob O in adjusted, assembled position threaded onto the outer end of spindle S. The knob O is assembled in operative position on spindle S by threading the hub 18 thereof onto the threaded outer end of spindle S until the inner reduced diameter end of the hub seats in the annular bore formed by the inturned flange 14a of the outer rose 14 in bearing relation with that flange, as will be clear by reference to Figs. 2, 7 and 9.

The inner knob I comprises a unit formed of a shank 17 similar to the shank of outer knob O, which is secured on and over an insert member or locking latch actuating hub member 30 which forms an element of the latch locking organization of my invention, and a knob forming cap member 19 secured at and around its inner side to the outer annular flange portion 17a of shank 17. The inner knob I is not threaded onto the inner end length of spindle S, but in accordance with my invention is mounted on the spindle with lost motion to provide for limited rotation of the hub 30 on and relative to the spindle. The hub 30 is formed with a smooth wall axial bore 31 therethrough of an internal diameter to rotatably receive the inner end length of spindle S. The inner knob I is assembled in operative position on spindle S by sliding the hub 30 onto the spindle until the inner reduced external diameter portion 32 of the hub 30 is received in the axial bore of the inner rose 15 which is formed by the inturned flange 15a of the rose, with such flange forming a bearing for the hub 30 and the inner knob I. The lost motion mounting of the hub 30 with the inner knob I and the manner in which the inner knob I is retained in position on spindle S for rotation of that spindle will be referred to and explained in detail hereinafter.

Thus, with the latch mechanism, including spindle S and the inner and outer knobs I and O, in assembled, installed position on the door D the latch bolt unit L may be operated to retract the latch bolt thereof for opening of the door, by rotation in either direction of either the inner or outer door knobs I or O, as will be readily understood by those familiar with this art.

Latch bolt unit

The latch bolt unit L which forms a part of my present invention, is of the tubular type and is adapted for general use as a plain latch bolt unit of the spindle actuated type, as well as a tubular latch unit for association with various special types of door latch mechanisms, such as the mechanism of the inside door set of the pres-

ent example. It is of a design and construction which can be readily manufactured in quantity production but which will assure positive precision operation with a minimum of failure under conditions of use.

Referring to Figs. 3 and 10 of the drawings, in particular, the unit embodies a case 100 which may be stamped, pressed or otherwise formed from a suitable sheet material to include a side-wall 101, and opposite edge, parallel walls 102 and 103 connected at one end by an end wall 104. In the present example installation, the wall 102 happens to be the upper wall, wall 103 the lower or bottom wall, and wall 104 the inner end wall. At the forward end case 100 is open and the walls 102 and 103 have at their outer end edges the upwardly and downwardly turned tongues 102a and 103a, respectively, by which the case has secured and attached to the forward end thereof a vertically disposed back plate 105 having a central opening 106 therethrough which, with the plate in assembled position on the forward end of case 100, is aligned with the open forward end of the case (see Fig. 8). A complementary face plate 107 is suitably secured on and covering the outer side of the inner or back plate 105. Face plate 107 is formed with a rectangular opening 108 therethrough which is aligned with opening 106 in the back plate 107. The rectangular opening 108 in face plate 107 slidably receives 30 therein the usual door latch bolt 99.

Case 100 is completed by the attachment thereto of a cap 109 which forms the side wall of the case opposite and parallel with side wall 101. Cap 109 at its forward end is provided with a forwardly extended tongue 109a by which it is secured to the back plate and face plate 107 in assembled position. The rear end of cap 109 is formed with a recess 109b which receives a tongue 104a projecting from the inner end wall 104 by which the rear end of the cap is attached in assembled position to case 100. Top wall 102 and bottom wall 103 are each formed of reduced width intermediate their forward and rear ends to provide the elongated, longitudinal seating edges 102b and 103b, respectively. Walls 102 and 103 at their forward ends at the open side of the case which receives the cap 109 thereover, are formed to provide the projecting tongues 102c and 103c, respectively. Seats 102d and 103d are formed by the edges of the walls 102 and 103, respectively, which connect tongues 102c and 103c with the elongated seats 102b and 103b. Walls 102 and 103 at the forward ends of the cut outs which form the seats 110 provide the transversely parallel tabs or tongues 102e, while at the rear ends of such cut outs, walls 102 and 103 are formed to provide the outwardly projecting tabs or tongues 102f, respectively.

The upper and lower walls 102 and 103 of case 100 are formed with inwardly extended cut outs or recessed portions therein adjacent but spaced from the inner end of the case to provide the similar, transversely aligned seats 110. These seats 110 are extended by forward undercuts in the walls 102 and 103 to provide the forwardly extended slots 110a. Wall 101 and cap 109 are formed with the circular openings 110 transversely therethrough, respectively, which with the unit in assembled relation are axially aligned for receiving therethrough the latch bolt actuating spindle S.

The case side wall forming cap 109 is formed with the laterally offset, longitudinal edge flanges 209c and the laterally offset transverse inner end

flange 109d, in which latter flange the recess 109b is formed. The flanges 109c terminate spaced from the forward end of the cap and the cap is formed intermediate its forward end and the forward ends of flanges 109c with the opposite side, laterally extending tongues 109d and the forward opposite recesses 109e. The offset longitudinal flanges 109c of the cap are formed with the pairs of opposite transversely aligned recesses 109f in locations for receiving therein the pairs of case tongues 102e and 103f, respectively.

In assembled position of cap 109 on case 100, tongues 102c and 103c seat in cap recesses 109e; cap tongues 109d seat on case seats 102d and 103d; 15 the offset flanges 109c of cap 109 seat on the elongated longitudinal edge seats 102b and 103b of case walls 102 and 103, and extend rearwardly over and across the cut out portions which form the inset seats 110; case tongues 102e and 102f are received in cap recesses 109f; and case tongue 104a is received and seats in recess 109b of the offset end flange 109d of cap 109. The tab or tongue 109a bent up from the forward end of cap 109 extends through opening 106 of back plate 105, being engaged over the adjacent edge portion of that opening, while the tongues 102a and 103a of case 100 also extend into back plate opening 106 and are engaged over adjacent edge portions of that opening.

The case closing cap 109 thus has in effect "snap" attachment to the case 100 in assembled position, so that it may be readily assembled on the case with the case assembled to the back plate 105 at the forward end thereof. The tab or tongue 109a may after assembly be bent slightly inwardly over and engaged with the cap to insure against cap displacement. It may be as readily bent outwardly sufficiently to enable ready detachment and removal of the cap from the case in the event that it should become desirable to open the case for repair or replacement of any of the parts of the latch bolt mechanism contained within the case. The complete case itself comprises but two (2) readily manufactured major components, namely the case 100 and cap 109, while the latch bolt receiving and mounting structure attached to the forward end of the case comprises but two (2) parts, namely, the back plate 105 and the face plate 107 which are readily assembled on the forward end of the case and to each other.

A hub or roll-back mounting, bearing member 112 having a circular bore 113 therethrough is mounted on seats 110 in position extending across case 100 between wall 101 and the cap 109 with the bore 113 thereof axially aligned with the wall bores 110. Bearing member 112 is formed with the opposite extended portions forming flanges 112a which engage seats 110 and at their forward ends are engaged in the undercut grooves 110a, respectively in walls 102 and 103. At the forward edge of bearing member 112 an inwardly turned flange 114 is provided which is formed curved or arcuate about the axis of bore 113 as a center. Flange 114 has an effective length equal to the spacing between the inner surfaces of walls 102 and 103 so as to fit in position therebetween. A hub or roll-back member 115 having a square opening 116 therethrough dimensioned to slidably fit and receive spindle S, is provided for rotatable mounting on and against the inner side of bearing member 112. Hub member 115 is formed with a curved forward edge 116 complementary with the inner curved side of arcuate flange 114 for slidable bearing engage-

ment with the flange. The curved forward edge 116 of roll-back or hub member 115 has its opposite ends extended outwardly beyond the body of the hub member to form the upper and lower lugs 117.

A yoke member 120 of generally elongated, rectangular form is slidably mounted and confined within case 100 for actuation by rotation of the hub member or roll-back 115 to retract and project the latch bolt 99. This yoke 120 includes a vertically disposed wall 121 having an elongated opening 122 therethrough with this wall in assembled position of the yoke in the unit disposed and slidably between the inner side of hub member 115 and the outer side wall or cap 109, as will be clear by reference to Fig. 8 in particular. At its forward, upper side the yoke has an inwardly bent guide and positioning finger 123 which has slidable engagement at its free end with the inner side of case wall 101. At its forward lower side yoke 120 is formed with an inturned flange 124 which also has at its inner free end, slidable bearing engagement with the inner side of case wall 101. Flange 124 is formed with a rectangular opening 125 therethrough. Yoke 120 bridges hub member 115 and the spindle S which extends therethrough in assembled position, and at its rear end between hub bearing member 112 and the inner end wall 104 of case 100, the yoke is bent inwardly for its full width to form the flange 126 thereacross which has slidable bearing engagement with the inner surface of wall 101, and which together with finger 123 and flange 124 at the forward end of the yoke, provides the positioning and aligning support for the yoke for reciprocation thereof within the case. The yoke 120 has lateral guiding support in the direction of cap 109 by slidable engagement with the inner side, flat surface provided by the portion of the cap contiguous thereto.

The yoke member 120 has formed and bent up therefrom at the upper and lower side edges of wall 121, the upwardly and downwardly projected ears 130, respectively. Ears 130 are located on wall 121 intermediate the length of the elongated opening 122 and in positions at the rear of and engaged by the upper and lower lugs 117, respectively, of the hub member or roll-back 115. Hence, in assembled position rotation of roll-back 115 in either direction by spindle S will cause the rearwardly moving lug 117 to engage its yoke mounted ear 130 to thereby force or slide the yoke rearwardly in case 100 in a direction to retract the latch bolt 99.

Latch bolt 99 of the latch unit L, may be considered to be of generally conventional design to provide the usual inclined face or surface for slidably engaging against the strike plate 81 (see Fig. 2) of a door frame. In this instance, latch bolt 99 is slidably positioned in and guided by the square hole 108 of face plate 107, and projected inwardly through the opening 106 of the back plate 105 which is attached to the forward end of case 100. Latch bolt 99 has suitably connected to the rear end thereof a tail piece 131 which extends inwardly a distance into case 100 and which is provided at its inner end with an upwardly projected nose forming a hook 132. The hooked inner end of tail piece 131 extends into the rectangular opening 125 of flange 124 of the yoke 120 in position with the upwardly extended nose of the hook 132 engageable against the inner side of flange 124 at the upper side of opening 125. Upon rearward movement of yoke 120 within case 100 the hooked inner end 132

of tail piece 131 being engaged with the yoke will draw the tail piece rearwardly and retract latch bolt 99. However, the latch bolt 99 with tail piece 131 is movable rearwardly and relative to and independently of yoke 120 by rearwardly acting forces applied to the latch bolt. Under these conditions the tail piece 131 slides freely rearwardly through yoke 124 completely independently of the yoke.

10 A coil expansion spring 132 is mounted on and over tail piece 131 under compression between the rear of the latch bolt 99 and the flange 124 of yoke member 120. Thus, the latch bolt when depressed or moved inwardly relative to yoke 120 places spring 132 under increased compression, so that, upon release of the inwardly acting forces on the latch bolt the latter is instantly projected outwardly to normal strike-engaging, door latching position.

15 The yoke member 120 is spring loaded and normally continuously biased to its forwardly projected position. With the unit L of my present invention the spring loading of the yoke 120 is effected by a coil expansion spring 133 which is inserted under compression within case 100 between the inner end wall 104 of the case and the inner end flange 126 of the yoke 120. When roll back 112 is rotated in either direction by rotation of the spindle S which extends transversely therethrough in assembled position, the yoke 120 is forced rearwardly against spring 133 and the latch bolt 99 is retracted. Upon release of the turning forces on spindle S the spring 133 acts to instantly move the yoke forwardly to return it to normal, latch bolt projected position. When the latch bolt 99 is retracted by rearward movement of yoke 120 against spring 133, the spring 132, however, is not further compressed. But when latch bolt 99 is depressed and retracted independently of yoke 120, spring 132 is compressed and in order to permit of such compression, spring 133 must not yield to the forces applied to the yoke by spring 132. Hence, spring 133 is formed heavier to exert a force greater than that of spring 132, so as to be unyielding under such conditions.

20 No claim is made herein to the design, arrangement and construction of the latch bolt unit per se, as such latch bolt unit is disclosed and claimed in my copending application Serial No. 271,492, as a division of this application.

Automatically releasable locking latch organization

25 In carrying out those features of my invention by which the latch mechanism including latch bolt unit L, can be releasably locked from the inside of the door, I have provided a locking member under the control of the button B, together with a dog or latch member under the control selectively of either the inner knob I or of the latch bolt 99, for releasably dogging the lock member in locked position.

30 The manually operable push button B for effecting locking and for effecting the dogging or latching of the locking member, in locked position, is positioned in an axial bore in the shell 19 of the inner knob unit I for free reciprocation therein. Referring now to Fig. 7 in connection with Fig. 10, button B is provided with a stem or pin 32 which extends axially inwardly therefrom and which is slidably received at its inner end in an axial bore 33 in spindle S which opens through the outer end of the spindle within the knob I. A coil expansion spring 34 is mounted

11

on and around stem 32 and acts to continuously bias button B and stem 34 outwardly to their normal position with the latch released or undogged and the locking member in unlocked position.

A square locking sleeve 40 is provided having an internal width to form a square opening through the sleeve to receive the spindle S with a smooth running fit, with the sleeve slidably mounted on the spindle. Locking sleeve 40 has an external width to slide into and from the square opening 21 and its forming flanges 21a of the latch plate 20, by reciprocation of sleeve 50 on spindle S under the control of the inner knob button B and its biasing spring 34.

The push button B is operatively connected with the locking sleeve 40 in such a manner that upon depression or inward movement of the button and its stem 34 relative to the inner knob I and spindle S, the locking sleeve 40 will be slid inwardly into spindle locking position in the square opening 21 of the latch plate 20. For this purpose I provide a relatively small diameter, wire type of push rod 41, and I utilize one of the longitudinal grooves 10 provided by the fluted form of spindle S, within which to reciprocally mount and confine this push rod. The diameter of push rod 41 is such that when positioned within its groove 10 of shaft S the rod is confined within the confines of the periphery of the spindle S, as will be clear by reference to Figs. 4, 5, 6 and 9. The push rod 41 in assembled position in a groove 10 extends outwardly from the outer end of spindle S along one side of stem 32 over the spring 34 mounted thereon to a point adjacent the inner end of the button B, where the push rod terminates as a radially projected pin 41a bent therefrom. (See Fig. 10.) A transverse or radial bore 32a (see Fig. 10) is formed in stem 34 and receives therein the pin 41a of push rod 41 to thus attach the push rod to the stem and button unit. Depression of button B and inward movement of stem 32 thus effects inward sliding movement of the push rod through the spindle groove 10. Reverse or outward movement of stem 34 slides the push rod outwardly through its receiving groove 10.

The square locking sleeve 40 is slidably mounted on the square spindle S in position thereon adjacent the outer side of the latch plate 20, the sleeve thus extending over and across the groove 10 within which push rod 41 is mounted. The push rod extends inwardly along spindle S in its groove 10 through locking sleeve 41 beneath one flat side wall of that sleeve. The push rod 41 adjacent its inner end is coined or provided with an outwardly facing flattened portion 42 having a length substantially equal to the width of the side wall of locking sleeve 41 positioned thereabove. Coined portion 42 provides at its opposite ends the shoulders 42a for engaging against the opposite edges of the locking sleeve side wall adjacent thereto. This coined inner end portion 42 of push rod 41 is so formed and arranged that in assembled relation on spindle S with locking sleeve 40, the adjacent side wall of the sleeve is seated therein and engaged by the opposite end shoulders 42a thereof, so that, the sleeve is reciprocated on spindle S by reciprocation of push rod 41 under the control of button B and its spring 34. Such formation of the coined or flattened portion 42 of push rod 41 is shown in Figs. 11 and 12 in particular, in connection with Figs. 9 and 10.

When the button B in the inside knob is depressed from its latch released position of Fig. 7,

12

to its latching or dogging position of Fig. 8, the push rod 41 is moved inwardly on spindle S with the outer shoulder 42a of the coined portion 42 of the rod engaging locking sleeve 40 and sliding this sleeve inwardly into the square hole 21 of the latch plate 20 which is secured in fixed position on door D. In such position the spindle S is locked against rotation and cannot be actuated by the outer knob O to operate the latch bolt unit L to retract the latch bolt 99 from its projected, door latching position. Upon release of the forces acting to depress button B against spring 34, in the absence of some other means for retaining locking sleeve 40 in its spindle locking position in latch plate 20, the spring 34 will instantly bias button B and its stem 34 outwardly and will thereby draw or slide push rod 41 outwardly and withdraw locking sleeve 40 from the square opening 21 in latch plate 20 to release the spindle S for door opening operation. Such latter position of the mechanism is shown in Figs. 2 and 7 of the drawings.

In this example embodiment of the invention, a washer 65 is mounted on spindle S in the completed assembly, at the inner side of latch plate 20. A lock ring 66 of the split, snap type engaged in suitable retaining notches in the spindle is mounted at the inner side of washer 65 to retain the washer against displacement inwardly on the spindle, the washer 65 thus forming a limiting stop for inward movement of locking sleeve 40 through latch plate opening 21, as clearly shown by Figs. 7 and 8.

The insert or hub member component 30 of the inner knob unit I has the smooth walled axial bore 31 therethrough which permits of lost motion or limited rotation of the inner knob on spindle S, as referred to generally hereinbefore. In this example, the lost motion mounting of the inner knob I on spindle S is accomplished by providing diametrically across the outer end of the hub member 30 a relatively wide milled groove 35. A positioning and movement limiting pin 36 having a diameter considerably less than the width of the groove 35 is mounted in and extends transversely through spindle S at the outer end of hub member 30, with the opposite end lengths of this pin positioned in and extending outwardly through groove 35 at opposite sides of the spindle S. Thus mounted and constrained by pin 35, the inner knob I may be rotated on and relative to spindle S within the range determined by the width of groove 35 and the engagement of the pin against the opposite side walls of the groove.

With the inner knob I having such lost motion mounting on the spindle S, I have devised a self-centering means therefor by which upon release of the knob after a locking latch releasing and latch bolt retracting rotation, the knob will be returned automatically to its normal, centered position on the spindle. Referring to Figs. 2, 6 and 10, the inner knob hub member 30 is formed with a pair of diametrically opposite axially aligned radial bores 37 therethrough opening at their inner ends into the axial bore 31 of the hub member. A ball 38 is confined in each of the bores 37 at the inner end thereof in engagement with spindle S, and is biased inwardly into engagement with spindle by an expansion spring 39. Each spring 39 is maintained under compression between the ball 38 at the inner end thereof and the knob shank 17 which extends over and closes the outer end of the bore 37. The balls 38 are thus spring loaded and continuously biased into and maintained in engagement

with the spindle S. The bores 37 are so located in hub member 30 that with that member in its normal position the balls 38 are engaged in grooves 10 of spindle S at the opposite sides thereof to thus yieldingly hold the hub member in centered position on the spindle. With the spindle S at rest, rotation of inner knob unit I in either direction independently of spindle S may be effected within the limits determined by pin 36 in the hub member groove 35. Such rotation of the hub member 31 will cam balls 38 against the side walls of the grooves 10 to thereby increase the compression of springs 39. Upon release of the turning forces acting on knob I, the spring biased balls 38 thereupon cam hub member 31 back to normal position with the balls centered in the grooves 10 at opposite sides of the spindle.

By a further feature of my invention I provide a latch 50 for releasably latching or dogging the locking sleeve 40 in locking position engaged in latch plate opening 21 against displacement therefrom. This latch 50 is under the control of and is released automatically from latching or dogging position, either by lost motion rotation of inner knob I on spindle S or by depression or retraction of the latch bolt 99 independently of the yoke 120 of the latch bolt unit L.

Referring to Fig. 10 in connection with Figs. 7, 8 and 9, the latch 50 is formed as a generally U-shaped structure comprising the slide frame or base 51 and the actuating leg 52 spaced therefrom and normally generally parallel therewith. The leg 52 is joined at one end with the adjacent end of the frame or base 51 by a curved or arcuate end wall 53 thereacross having the opposite outwardly projected ends 53a at the opposite sides of the latch member 50. Both the frame or base 51 and the leg 52 are formed transversely open throughout their major area to provide the elongated, longitudinally disposed openings 51a and 52a therethrough for receiving spindle S and for permitting movements of the latch member transversely across and relative to the spindle. The arcuate, transverse end wall 53 of latch member 50 has formed therefrom at the outer side end of the frame or base 51 an inwardly extending dog or latch tongue 54 which is disposed along the longitudinal center of the latch member. This dog 54 provides the opposite side edges 54a as inclined inwardly and converging at the inner pointed end of dog 54. (See Fig. 9.)

The leg 52 of latch member 50 is adapted to be bent laterally outwardly from its normally, generally parallel relation with frame or base 51 in order to adjust the organization of which it forms a component, to doors of varying degrees of increased width. With the leg 52 in its normally parallel relationship with 51, the latch is then adapted for use with an installation on a door of minimum width of the range of widths to which the unit is adapted. The latch actuating leg 52 may be rendered bendable for adjustment in any suitable manner, by utilizing a suitable material and a thickness thereof such that the leg may be readily bent outwardly to the desired adjusted position on the job at the time of installation. (See Fig. 9.)

The latch plate 20 slidably mounts and receives thereon the latch member 50 and to this end plate 20 has struck up therefrom the spaced inwardly turned guides 22 for slidably receiving therebetween the opposite longitudinal edge portions of the slide frame or base 51 of the latch member 50. These guides 22 are positioned spaced apart

vertically between the outer end edge 20a of plate 20 and the square opening 21 formed by flanges 21a in the plate. Guides 22 are located on the outer side of plate 20 with the plate assembled in installation on a door, the flanges 21a defining the square opening 21 being extended from the inner side of the installed plate. A generally rectangular opening 23 is formed through latch plate 20 intermediate square opening 21 and the inner end edge 20a (see Fig. 10) for receiving therein and therethrough the end of latch member 50 connected by end wall 53. The latch member is assembled in operative mounted position on latch plate 20 with the guide frame or base 51 thereof slidably received in and between and constrained to horizontal sliding movements longitudinally on plate 20 by the guides 22. The joined ends of frame 51 and leg 52 with the end wall 53 are received in and through plate opening 23 with the end wall 53 and latch actuating leg 52 positioned at the inner side of the plate, as will be clear by reference to Fig. 8 in particular. Thus mounted, the dog or latch tongue 54 is located at the outer side of latch plate 20 on the inner side of spindle S and inner knob insert or hub 30 in relation to the outer edge 3 of door D in installed position.

The latch member 50 is spring loaded and is continuously biased outwardly to thereby continuously bias the dog 54 radially inwardly toward spindle S and the inner knob hub member 30. Such biasing in the present example is effected by torsion spring 55 which is mounted on a lug struck up and bent laterally outwardly from the upper edge portion of plate 20 (see Fig. 9). Spring 55 has its opposite ends providing the spring arms 55a and 55b. In assembled position arm 55a of spring 55 is engaged under the inturned flange 15b of outer rose 15 which is mounted over and secured on latch plate 20, while the opposite arm 55 is engaged with and against the outer side of the vertically disposed arcuate end wall of latch member 50 to thereby continuously bias member 50 outwardly on and across latch plate 20 to move the dog or latching tongue 54 to its inwardly projected position.

The latch member 50 is actuated from its inwardly biased position releasably dogging the square sleeve 40 in spindle locking position engaged in square hole 21 of latch plate 20, by rotation in either direction of the inner knob I on and independently of spindle S. Such latch releasing actuation of member 50 is effected by camming action between the inner end of the inner knob hub member 30 and the dog or latching tongue 54 of the latch member 50. The inner end of hub member 30 is formed of reduced external diameter, and diametrically opposite, radially disposed slots 60 are milled or otherwise suitably formed in and opening through and across the inner end of hub member 30. The side edges formed by hub member 30 at opposite sides of each camming slot 60 are formed to provide outwardly diverging, inclined camming edges 60a. In assembled position, inner knob hub member 30 extends inwardly through the axial bore of outer rose 15 formed by annular flange 15a and assumes a position at the outer side of the slide frame 51 of latch member 50 with the dog or latching tongue 54 of member 50 projecting into the adjacent camming slot 60 of the hub member, as clearly shown by Fig. 8 of the drawings.

Thus, it will be apparent that rotation of inner

knob I independently of spindle S will cause one or the other of the camming edges 60a of slot 60 to engage one or the other of the inclined edges 64a of latch member dog 54 and cam the latch member 50 radially outwardly relative to spindle S against the action of the spring unit 55. In assembled position with the locking sleeve 40 in its normal position moved outwardly on spindle S free of locking plate 20, the latch member 50 is in its normal position of inward bias with the inner end of dog 54 yieldingly riding on the adjacent outer surface of the locking sleeve. In this example, dog 54 rides on a corner between flat walls of sleeve 40, as shown by Fig. 9. When, however, the locking sleeve 40 is moved inwardly by depression of button B to locking position engaged in the square opening 21 of locking plate 20, the width of sleeve 40 is such that the outer end thereof clears the inner end of dog 54, and the latch member 50 under the bias of spring 55 moves further outwardly to instantly move dog 54 inwardly over outer end of locking sleeve 40 to position engaging and holding the locking sleeve in locked position against the forces applied thereto by spring 34. This spring 34 constantly acts to move the sleeve outwardly on the spindle S to return it to position disengaged from locking plate 20 and unlocking spindle S for rotation by outer knob O.

In accordance with my invention the latch member 50, aside from being operable to release locking sleeve 40 from locked position by the inner knob I, is also operable to released or undogging position by depression of latch bolt 99 to retracted position independently of spindle retraction of the latch bolt. In this example I carry out this feature of the invention by providing a yoke member 70, the construction of which is clearly shown in Fig. 10. This yoke member 70 comprises the opposite, parallel legs 71 and 72 connected at one end by a cross member 73 which is formed at one side edge with an outwardly projecting flange 73a. Cross member 73 and flange 73a are formed with a rectangular opening 74 therethrough of cross sectional dimensions which will permit of the latch bolt tail piece 131 and hooked inner end 132 thereof being passed through this opening to mount the yoke on the tailpiece. The opposite free ends of legs 71 and 72 are provided with the laterally outturned flanges 75, one of which is adapted when in assembled position to engage the outer free end of the actuating leg 52 of latch member 50.

The yoke 70 is mounted and assembled on latch bolt tail piece 131 with the cross member 73 and its flange 73a positioned between the inner end of the latch bolt and outer end of the latch bolt actuating spring 132, as will be clear by reference to Fig. 8. The legs 71 and 72 of yoke 70 extend inwardly along the case walls 101 and 109, respectively, and the opposite outturned end flanges 75 of these legs extend freely through openings 76 formed in case wall 101 and cap 109. In this instance leg 71 happens to be the leg assembled at the outer side of case 100 and the outturned flange 75 thereof projects outwardly through opening 76 in position engaged at its inner side by the outer free end of latch member actuating leg 52. Depression of latch bolt 99 and its tail piece 131 independently of the spindle actuated yoke 120, will force yoke 70 inwardly and thus through the engagement of the outturned flange 75 of leg 71, with the end

of latch member leg 52, force latch member 50 inwardly to thereby move the dog 54 to position releasing locking sleeve 40.

That leg of the yoke 70 which is not positioned for engagement with latch member actuating leg 52, in this instance leg 72, provides by its outturned flange 75, the means by which an emergency operation of the latch member 50 to release the locking member 40 from locked position may be effected by a person from the outside of the door D. To this end an opening or bore 80 is provided through the front or outer wall of the outside rose 14 in line with the outturned flange 75 of leg 72 of yoke 70. By inserting a suitable instrumentality such as a screw driver, nail, hairpin or the like stiff article, through opening 80 into engagement with flange 75 of leg 72, the yoke 70 may be forced inwardly to thus force leg 71 inwardly to move latch 50 to position releasing sleeve 40 for return under the action of spring 34 from engaged, locking position in the square opening 21 of the locking plate 20 to unlocked position disengaged from the latch plate.

Assembly and operational summary

The assembly and the installation on a door, such as door D, of the door locking, latch mechanism of the invention will be clear from the foregoing description and from Figs. 1, 2, 7 and 8 of the drawings in particular.

In Figs. 1, 2 and 7, the organization is shown in its normal position for retraction of latch bolt 99 for door opening by operation of either the outer knob O or the inner knob I. Rotation of either knob in either direction rotates spindle S and, with this spindle extending through and engaged in the square opening of the roll-back 115 of the latch bolt unit L, the roll-back will be rotated to draw yoke 120 rearwardly and retract the latch bolt 99 from its door locking position engaged in usual strike plate 81, shown more or less schematically in Fig. 2 of the drawings. If it is the inner knob I that is actuated to cause retraction of latch bolt 99, it will be understood that the knob will be first rotated through its lost motion on spindle S until pin 36 has engaged the sides of the slot 35 in the end of the hub member 39, after which continued rotation of the knob will rotate the spindle. Release of the knob I will bring into play the self-centering means comprised by the balls 38 and springs 39 to restore the knob to its centered position on spindle S.

If now a person at the inside of door D wishes after closing the door to lock the latch mechanism against retraction of the latch bolt 99 from the outside of the door, the push button B slides the locking sleeve 40 inwardly on spindle S until the sleeve is engaged in the square locking hole 21 of latch plate 20. The latch plate being a fixed member, the spindle S is thus secured against rotation by the outer knob O, so that the latch bolt 99 cannot be retracted or the door opened from the outside by outside knob operation.

In the normal unlocked position of the latch mechanism, the locking dog or tongue 54 of latch member 50 yieldingly rides on the adjacent side of the locking sleeve 40. When, however, this sleeve is moved inwardly by depression of button B and assumes locking position in square opening 21 in latch plate 20, latch member 50 is biased inwardly by spring 55 and the dog 54 is projected inwardly over and across the outer

end of sleeve 40 and thereafter holds that sleeve from retraction by spring 34 from locking position. The locked position of the latch mechanism is shown in Fig. 8 of the drawings.

When a person at the inside of the door wishes to open the door with the mechanism locked, he does so by normal rotation of the inner knob I. When this normal rotation is started, due to the lost motion mounting of the inner knob I on spindle S, hub member 30 is first rotated on and independently of spindle S, and as the dog 54 is located in a camming slot 60 of hub member 30, the dog 54 is thereupon cammed outwardly with latch member 50 against the action of latch member spring 55, until dog 54 is clear of the outer end of sleeve 40. Immediately upon dog 54 clearing sleeve 40, spring 34 takes control and returns button B to outwardly projected position and thus through push rod 41 draws sleeve 40 outwardly on spindle S from locking position engaged in latch plate 20 to unlocked position disengaged from the latch plate. Hence, the entire organization is then returned to normal, unlocked position for door opening by either the inner knob I or the outer knob O.

If through inadvertence or willfully, someone depresses button B with the door swung to open position clear of the strike plate 81, to thereby lock the latch mechanism against actuation by the outside knob O, and the door should happen to be swung to closed position, the latch member 50 and its locking dog 54 will be released automatically and the mechanism will restore to unlocked position. This is effected by the yoke 71 in the latch bolt unit L. As the door is closed and the latch bolt 99 is depressed by engagement with strike plate 81, yoke 70 is forced inwardly by the latch bolt and latch member 50 is moved radially outwardly relative to the spindle until the dog 54 clears the locking sleeve. The locking sleeve 40 is then restored to unlocked position automatically by the action of spring 34.

Thus, in using a door equipped with the door locking latch mechanism of my invention, no concern need be given by the user to releasing the latch mechanism from locked position, as under all conditions of operation such release is automatically effected either by normal door knob operation to open the door or by depression of the latch bolt 99 in the normal functioning of that bolt by engagement with the strike plate 81 in the closing of the door if button B has been depressed to locking position with the door in open position.

It will also be evident that various other changes, variations, modifications, substitutions, eliminations and additions may be resorted to without departing from the broad spirit and scope of my invention, and, hence, I do not intend to limit the invention in all respects to the exact and specific disclosures hereof, except as may be required by intended specific limitations thereto appearing in certain of the appended claims.

What I claim is:

1. In a door latch mechanism, in combination; a latch bolt actuating, rotary spindle; a latch bolt unit including a latch bolt mounted for movements between a projected position and retracted position, and actuating mechanism for retracting said bolt from projected position, said latch bolt being depressible from projected position to retracted position independently of said actuating mechanism, and said rotary spindle being operatively coupled with said latch bolt

actuating mechanism; a locking member mounted for actuation between a position locking said spindle against rotation and a position releasing said spindle for rotation; an inner knob mounted on said spindle for rotating the spindle; a manually operable member mounted on said inner knob and being operatively connected with said locking member for actuating said member to spindle locking position; a latching member mounted for actuation to and from position releasably latching said locking member in locked position; and an actuating member connected with said latch bolt and being adapted to engage said latching member by independent depression of said latch bolt to retracted position to actuate said latching member to unlatched position.

2. In a door latch mechanism, in combination, a latch bolt actuating, rotary spindle; a latch bolt unit including, a latch bolt mounted for movements between a projected position and retracted position, an actuating mechanism for retracting said bolt, said latch bolt being depressible from projected to retracted positions independently of said actuating mechanism, and said rotary spindle being operatively coupled with said latch bolt actuating mechanism; a locking member mounted for actuation between a position locking said spindle against rotation and a position releasing said spindle for rotation; a latching member mounted for actuation to and from position releasably latching said locking member in locking position; and an actuating member connected with said latch bolt and being adapted to engage said latching member by independent depression of said latch bolt to retracted position to thereby actuate said latching member to unlatched position.

3. In a door latch mechanism, in combination; a latch bolt actuating, rotary spindle; a latch bolt unit including, a latch bolt mounted for movements between a projected position and retracted positions, and an actuating mechanism for retracting said latch bolt from projected position, said rotary spindle being operatively connected with said latch bolt actuating mechanism, and said latch bolt being mounted for depression to retracted positions independently of said actuating mechanisms; locking means mounted for actuation between a position locking said spindle against rotation and a position releasing said spindle for rotation; a latch member mounted for actuation to and from position releasably latching said locking means in spindle locking position; said latch member including an actuating leg; a yoke member connected to said latch bolt and including inwardly extending legs, one of said yoke member legs being adapted to engage said latch member leg upon depression of said latch bolt, and said latch member leg being laterally bendable outwardly to angularly disposed positions of adjustment relative to said yoke member.

4. In a door latch mechanism, in combination; a rotary spindle; a knob mounted on said spindle for independent rotation thereon; means limiting rotation of said knob in either direction on said spindle; a locking member mounted for actuation between a position locking said spindle against and a position releasing said spindle for rotation; a manually operable member mounted in said knob; operative connections between said manually operable member and said locking member for actuation of the latter member to spindle locking position by operation of said

manual member; spring means adapted to continuously bias said locking member from spindle locking to spindle releasing position; a latch member mounted independently of said locking member and of said knob for movements to and from position engaged with and latching said locking member in locked position; spring means adapted to continuously yieldingly bias said latch member to latching position; said latch member being in operative engagement with said locking member and being adapted to be actuated automatically to position latching said locking member in locking position by movement of the latter from spindle releasing to spindle locking position; and an actuating member operatively connected with said knob and being adapted to be actuated thereby to engage and move said latch member to position releasing said locking member when said knob is rotated in either direction on said shaft.

5. In a door latch mechanism, in combination; a latch bolt actuating spindle; a knob mounted on said spindle for rotating the spindle; a latch bolt unit including, a latch bolt mounted for movements between projected and retracted positions, and actuating mechanism for retracting said bolt from projected position; said latch bolt adapted to be depressed from projected position to retracted position independently of said actuating mechanism; a locking member mounted for movements between position locking said spindle against rotation and position releasing said spindle for rotation; a latch member mounted for movements between a position latching said locking member in locked position and a position releasing said locking member; means operatively connected with said knob adapted to be actuated by rotation of the knob for moving said latching means from latching position; and means operatively connected with said latch bolt adapted to be actuated by independent depression of said bolt for engaging and moving said latching member from latching position to position releasing said locking member.

6. In a door latch mechanism, in combination; a latch bolt actuating spindle; a latch bolt unit including, a latch bolt mounted for movements between a projected and a retracted position; said spindle being operatively connected with said latch bolt actuating mechanism, and said latch bolt being arranged and mounted for depression from projected to retracted position independently of said actuating mechanism; a locking member mounted for movements between a position locking said spindle against and a position releasing said spindle for rotation; a latch member mounted for displacement to and from a position releasably latching said locking member in its spindle locking position; and a member operatively connected with said latch bolt and adapted to be engaged with said latching member to release the latter from latching position by movement of said latch bolt independently of said latch bolt actuating mechanism.

7. In a door latch mechanism, in combination; a latch bolt actuating spindle; a knob mounted on said spindle for rotating the spindle; a latch bolt unit including, a latch bolt mounted for movements between a projected position and a retracted position, and actuating mechanism for retracting said latch bolt from projected position; said latch bolt being mounted and arranged for depression from projected to retracted position independently of said actuating mechanism; a locking member mounted for movements be-

tween a position locking said spindle against and a position releasing said spindle for rotation; a latch member mounted for movements to and from position engaged with and releasably latching said locking member in locked position; an actuating member connected with said knob and adapted to be operated by rotation of said knob to engage and move said latch member from latching position engaged with said locking member to position releasing the locking member; and a member operatively connecting said latch bolt and said latch member adapted to be operated by independent depression of said latch bolt to displace said latch member from latching position to position releasing said locking member.

8. In a door latch mechanism, in combination; a rotary spindle; a knob mounted on said spindle for independent rotation in either direction thereon; means limiting rotation of said knob in either direction in said spindle to a predetermined range of rotation; biasing means adapted to continuously yieldingly bias said knob to a predetermined intermediate position in the range of rotation of said knob on said spindle; a locking member mounted for movements between a position locking said spindle against and a position releasing said spindle for rotation; mechanism for moving said locking member to spindle locking position; a latch member mounted for movements to and from a position releasably latching said locking means in its locked position; and means operatively connected with said knob adapted to be actuated by independent rotation of said knob in either direction from its said intermediate position on said spindle for actuating said latching member from latching position to release said locking means.

9. In a door latch mechanism, in combination; a plate adapted to be mounted in fixed position and having an opening therethrough; a rotary spindle adapted to be mounted in position extending through said opening; a locking sleeve slidably mounted in position on and around the exterior of said spindle for positive rotation with the spindle; said sleeve being mounted on said spindle at one side of said plate and being slideable longitudinally of said spindle to and from position received in said plate opening in non-rotary engagement with said plate to lock the spindle against rotation; a knob unit mounted on said spindle for rotation independently thereof; means limiting rotation of said knob in either direction on said spindle; spring means adapted to continuously bias said locking sleeve outwardly from spindle locking position received in said plate opening; manually operable means for moving said locking sleeve into locking position in said plate opening; a latch member mounted on said fixed plate independently of said locking sleeve for movements radially toward and from said locking sleeve and spindle; said latch member being positioned on said plate to slidably engage the adjacent side of said sleeve when the latter is in position out of locking engagement in said plate and to engage the adjacent end of said sleeve when the latter is in locking position in said plate opening to thereby latch the sleeve against displacement; spring means adapted to continuously bias said latch member to latching position; and said knob being provided with camming surfaces rotatable therewith adapted to engage said latch member upon rotation of said knob unit in either direction to cam said latch member from position latching to position releasing said locking sleeve.

10. In a door latch mechanism, in combination; a plate member adapted to be mounted in fixed position and having an opening therethrough; a rotary spindle adapted to be mounted in position extending through said opening in said plate member; a locking sleeve member slidably mounted on the exterior of said spindle for rotation therewith as a unit, said locking sleeve member being mounted on said spindle in position at one side of said fixed plate member for movements longitudinally of said spindle to and from position received in said plate member opening in non-rotary engagement with the plate member to lock said spindle against rotation; a knob on said spindle mounted for limited rotation in either direction on and relative to the spindle; means adapted to limit rotation of said knob on said spindle; spring means adapted to continuously bias said locking sleeve member from locking position in said plate member opening; manually operable means for moving said locking sleeve member into locking position in said plate member opening; a latch member mounted on said plate member independently of said locking sleeve member for movements on said plate member to and from latching position releasably locking said locking sleeve member in locking position against said locking sleeve member biasing means; means adapted to continuously bias said latch member to latching position; and means connected with and adapted to be actuated by limited rotation in either direction of said knob on said spindle for engaging and moving said latch member from latching position to position releasing said locking sleeve member.

11. In a door latch mechanism, in combination; a plate adapted to be mounted in fixed position and having an opening therethrough; a rotary spindle adapted to be mounted in position extending through said opening; a locking sleeve member slidably mounted on said spindle for rotation with the spindle, said sleeve being mounted on said spindle at one side of said plate for movements thereon longitudinally thereof to and from position received in said

plate opening in non-rotary engagement with said plate to lock the spindle against rotation; a knob unit on said spindle including, a knob hub mounted for limited rotation in either direction on and independently of said spindle; means adapted to continuously bias said locking sleeve member from spindle locking position in said plate opening; manually operable means for moving said locking sleeve member into locking position in said plate opening; a latch member mounted on said plate independently of said locking sleeve member for movements to and from a latching position releasably engaged with and latching said said locking sleeve member in spindle locking position; means adapted to continuously bias said latching member to its said latching position; and said knob hub being formed to provide camming surfaces for engaging said latch member upon independent rotation of said knob unit in either direction on said spindle to cam said latching member from locking sleeve latching position to position releasing said sleeve.

GOTTHARD HAGSTROM.
